UNITED STATES PATENT OFFICE.

WILLIAM M. COOK, OF WARREN, OHIO.

GAME-BOARD.

1,087,351.

Specification of Letters Patent.

Patented Feb. 17, 1914.

Application filed March 9, 1912, Serial No. 682,648. Renewed July 3, 1913. Serial No. 777,340.

To all whom it may concern:

Be it known that I, WILLIAM M. COOK, a citizen of the United States, residing at Warren, in the county of Trumbull and 5 State of Ohio, have invented certain new and useful Improvements in Game-Boards, of which the following is a specification.

This invention relates to improvements in game-boards.

10 The object of my invention consists in providing a game-board for the playing of a game similar to pool or other analogous games which are played with cues and balls.

The nature and characteristics of my 15 game-board, which distinguishes it from all others, may be stated as follows: In the ordinary game of pool the player aims to impel a ball into a pocket and there are no obstructions placed at or near any pocket on 20 the pool game-board, but in a modified game of pool playable on my game-board there is a ball resting on the game-board near each pocket, the balls having designated varying values, and a player has to cause 25 his ball to hit a flap with sufficient force to cause, by a mechanical expedient, one of said designated balls to fall into its adjacent pocket.

With the above and other objects in view 30 my invention consists in the combination, arrangement, and details of construction disclosed in the drawings and description, and then more particularly pointed out in the appending claims.

35 In the drawings, wherein similar reference characters designate similar parts wherever shown, Figure 1 is a top plan view of my game-board, Fig. 2 is a side elevation thereof, Fig. 3 is a longitudinal sectional view showing the part on which the balls roll back to the player after they have passed through the pockets, Fig. 4 is a fragmental view of the bottom of my game-board showing in detail the means for holding the flap 40 in operative or inoperative positions, Fig. 5 is a section of the game-board taken on a line X—X of Fig. 1, Fig. 6 is a fragmental sectional view of the game-board taken on line Y—Y of Fig. 1 showing a flap in unlocked position, and Fig. 7 is a detail view of the flap showing it in locked position.

45 Referring to the drawings which are merely illustrative of my invention the game-board 1 is preferably rectangular in contour and forms a convenient tray which

is supported on a table 2 resting on legs 3, said table being formed with an inclined bottom 4 extending throughout its full length and rising highest at the end where the ball receiving parts of my game-board 50 are mounted in position. The tray 1 is formed with a depending extension 5 which engages the surface 6 of the table 2, which surface forms the end of the table from which point the bottom 4 begins to slope 65 downwardly. Mounted on the tray in parallel relation with the part 7 thereof is an up-standing wall 8 between which and the part 7 the balls will initially be placed. At the rear of the wall 8 are mounted upon the 70 sides of the tray the inclosures 9, in which the players will place their score balls when the same shall have rolled down the bottom 4 of the table 2, said table having secured to the sides thereof pins 10 upon which are 75 fulcrumed lever arms 11 formed at their outermost ends with transverse elongated recesses 12, through which project pins 13 mounted upon the sides of the tray 1, each arm 11 normally held in an inclined position to hold the tray 1 against displacement over the table 2, and being movable to an 80 opposite inclined position to become free of the pins 13.

Disposed adjacent the end of the tray opposite the part 7, and arranged in an alining series are the ball guiding and discharging members 14, each of said members being composed of a loop part 15 which is formed of suitable metal, the middle portion being 85 bent upon itself to form the loop part 15 and the ends being separated and arranged in parallel relation, said ends being designated 16 and serving as a guide for a ball. It will be noticed that the members 14 are 90 formed of convenient widths and that they are arranged in staggered relation upon the tray 1 and it will also be understood that any number of the members may be provided and that their arrangement may be 95 changed without departing from the scope of my invention. Staples 17 are mounted upon the tray 1 and are disposed in close contiguity to the guiding ends 16 of the members 14, and in advance of each of the 100 staples 17 is another staple 18 so that a ball may either pass through said staples and between the guiding part of any of the members 14 or may strike against either of said 105 last-named staples and rebound or deviate in 110

its path so as to enter one of the members 14 not aimed for by the player. A ball receiving opening 19 is formed in the tray 1, and adjacent to it is another opening 20 into which projects a push-button 21 for a purpose about to be described. The last-named openings are both surrounded by the looped portion 15 of the member 14. The arrangement of the openings is the same in the case of all of the members 14.

The push-button 21 is secured by any suitable means such as screws 22 upon a flexible or spring metal flat plate 23 secured to the bottom of the tray 1 by a bolt 24 tapped through it at one end only, whereby said plate will be free to move when pressed downwardly by the push-button 21. In advance of the openings 19 and 20 is a flap 25 which is formed with a shank portion 26 passing through the relatively long opening 27 formed below the tray 1 with a right-angled portion consisting of a central looped part 28 and the parts 29 and 30 which serve as trunnions for the looped part 28, and said last-named parts are held in alining position and against displacement by staples 31. Normally, a ball 32 having a designated value for the player is arranged to fit over each opening 20, and to be forced upwardly by the push-button 21 whereby it may fall into the opening 19 and upon the inclined bottom 4 of the table 2, and this will take place when the flap 25 is moved to an unlocked position, said flap being normally held in locked position by the spring metal plate 23 bearing against the under side of the looped part 28 carried by said flap, and when in locked position the flap 25 will be obliquely disposed and at an acute angle with respect to the tray 1, so that by moving said flap to a substantially vertical position the loop 28 may ride clear of the plate 23 to cause said plate to engage the upper surface of said loop. It is to be noticed that the spring metal plate 23 bearing against the under side of the loop or projection 28 will cause the shank of the flap to bind against the surface 25' of the opening 27, and also that the loop 28 is disposed at an obtuse-angle with respect to the shank of the flap 25, and when said shank is bearing against the surface 25' said loop will be spaced below the bottom of the tray 1 and still hold said spring plate under tension. The flap 25 when in a locked position will incline against the surface 25' and after being struck by a ball assumes the upright position shown in dotted lines in Fig. 7. It will thus be seen that the flap 25 may bear obliquely against the surface 25' against the tension of the spring plate 23, as well as when said plate is not under tension, as shown in Fig. 6; but said flap, when said plate is not under tension, is movable so as to occupy the vertical dotted line position

shown in Fig. 7, within the limits of the opening 27 between opposite edges of which it may be moved. In either case the plate 23 will when depressed, engage the loop 28 so as to first tilt said flap from oblique to vertical position, and then, after it has moved under said loop it will, on recoiling, re-engage said loop to hold said flap in engagement with the surface 25'. As the plate 23 moves from its position under to that over the loop 28 the push-button 21 will move upwardly in the opening 20 with considerable force, due to the elastic tension of said plate, and as the ball 32 seats in said last-named opening it will be quickly shot upwardly, and the tray being supported in a truly horizontal plane, the ball 32 will fall through the opening 19 and upon the inclined bottom 4 formed upon the table 2. A flap 25 is disposed in each of the members 14 and is disposed substantially at a median line with respect to the parallel ends 16 of each of the members 14, and it will be understood that the spring metal plates 23 are put under tension when the push-buttons 21 are moved downwardly in the openings 20, and will therefore, rebound when the loops 28 are released therefrom.

The game-board will be used as follows: Only the important and essential features of the game will be described. A player takes a cue 33 in his hand, places a ball upon the tray 1, and by means of this cue impels said ball forwardly. The balls 32 seating in the openings 20 are of varying values and the player aims his cue ball so as to strike one of the flaps 25 whereby one of the balls 32 may be shot so as to fall into one of the openings 20. If the ball impelled has been properly directed it will pass through the staple 18 and the staple 17 into the guide formed by end 16 of a member 14. Flaps 25 must be held locked before the game can be played, otherwise there will be no upward movement of the push-button 21 to throw the ball 32 into an opening 19, and the player can very easily lock a flap, when a ball is not over said push-button, by forcing the narrow end of his cue over and against said push-button, and thereby causing the spring metal plate 23 to snap under the loop 28 thereby causing said loop to overlie the spring metal plate 23 and said flap to assume its normal oblique position. The cue ball having passed between the guides 16, as aforesaid, will strike the flap 25 and move it forwardly to unlocked position thereby releasing the loop 28 from said spring metal plate 23, and causing said plate to rebound and in so doing to quickly move the push-button 21 upwardly into its opening 20, and a ball 32 resting on said push-button will be thrown by said push-button into and through the opening 19 and will then drop and roll upon the inclined bottom 4.

4 of the table 2 so that it can be taken by the player and placed in one of the inclosures 9 formed upon the tray 1. A player having thus made a hit will lock the flap 5 which he has unlocked. It is obvious that the ball may strike any of said staples and be caused to enter any of said guides formed upon the members 14 and either strike the flap 25 or lacking sufficient force roll back 10 to the player.

Numerous modifications may be resorted to in practice without departing from the details of construction herein disclosed.

What I claim and desire to secure by Letters Patent is:

1. A game-board comprising a tray, means for holding said tray in an elevated position, a plurality of members, each composed of a guide for a ball merging with a relatively 20 larger inclosure, arranged in series upon said tray, a flap disposed at a point between said inclosure and guide, said tray being formed with oppositely arranged openings surrounded by said inclosure, a push-button 25 projecting into one of said openings upon which a ball rests, said push-button being arranged to be forced against said ball to throw it into the opening adjacent to its own, and means whereby the push button is 30 actuated when the flap is hit by a ball.

2. A game board comprising a tray, balls thereon, a table for supporting said tray, ball stalls on said tray, said table having an inclined surface, a plurality of openings in 35 said stalls, means in said stalls for projecting a ball, a cue ball adapted to operate said means.

3. A game-board comprising a tray, means for holding said tray in an elevated position, a plurality of members, each composed of a guide for a ball merging with a relatively larger inclosure, arranged in series upon said tray, a flap disposed at a point between said inclosure and guide, said tray 45 being formed with oppositely arranged openings surrounded by said inclosures, a push-button projecting into one of said openings upon which a ball rests, said push-button being arranged to be forced against 50 said ball to throw it into the opening adjacent to its own, means whereby the push-button is actuated when the flap is hit by a ball, means upon said tray for causing a ball thrown into said last-named opening to 55 return to a player, a wall adjacent the forward end of said tray between which and said end the balls are held, and relatively small members formed at the sides of said tray for holding a number of balls.

4. A game-board comprising a tray, the table upon which said tray is mounted, a plurality of members arranged in series upon said tray and composed each of a guide for a ball and an integral and wider loop, 65 a flap mounted within said loop, said tray

formed with oppositely arranged openings inclosed by said loop, a push-button projecting in one of said openings upon which a ball rests, means for impelling said push-button upwardly through its openings to 70 throw the ball resting on it into its opposing opening, and means for latching said flap, said flap when released actuating said first-named means, said push-button when moved downwardly actuating said last-named 75 means.

5. A game-board comprising a tray, a table upon which said tray is mounted, a plurality of members arranged in series upon said tray and composed each of a guide for a ball and an integral and wider loop, a flap mounted within said loop, said tray formed with oppositely arranged openings inclosed by each loop, a push-button projecting in one of said openings upon 80 which a ball rests, means for impelling said push-button upwardly through its opening to throw the ball resting on it into its opposing opening, means for latching said flap, said flap when released actuating said 85 first-named means, said push-button when moved downwardly actuating said last-named means, and means for returning the ball thrown by a push-button to a player.

6. A game-board comprising a tray, a table upon which said tray is mounted, a plurality of members arranged in series upon said tray and composed each of a guide for a ball and an integral and wider loop, a flap mounted within said loop, said tray formed with oppositely arranged openings inclosed by each loop, a push-button projecting in each of said openings upon 90 which a ball rests, means for impelling said push-button upwardly through its openings to throw the ball resting on it into its sister opening, means for latching said flap, said flap when released actuating said first-named means, said push-button when moved 95 downwardly actuating said last-named means, an inclosure for players' balls upon said tray, and inclosures for the score balls of each player.

7. A game-board comprising a tray, a table upon which said tray is mounted, a plurality of members arranged in series upon said tray and composed each of a guide for a ball and an integral and wider loop, a flap mounted within said loop, said tray formed with oppositely arranged openings inclosed by each loop, a push-button projecting in one of said openings upon 115 which a ball rests, means for impelling said push-button upwardly through its openings to throw the ball resting on it into its sister opening, means for latching said flap, said flap when released actuating said first-named means, said push-button when moved 120 downwardly actuating said last-named means, means for returning a ball thrown 125

by a push-button to the player, an inclosure for the balls of the players, and separate inclosures for the score balls of each player.

8. A game-board comprising a tray, a table for supporting said tray, a longitudinally inclined bottom upon said table, a plurality of members arranged in series upon the tray, each of said members composed of a ball receiving and guiding part 10 at and an integral loop, spaced-apart staples in advance of and in alinement with the guide of each member, a flap in each loop consisting of a button above the tray and a tiltable shank terminating below said tray 15 in right-angular rotatable part, said tray formed with oppositely arranged openings surrounded by each loop, a spring metal member secured at one end to the bottom of said tray barring one of said openings, a 20 block upon said spring metal member projecting in said last-named opening upon which a ball rests, and an offset formed upon said rotatable part, said block arranged to depress said spring metal plate to 25 cause it to snap under said offset to cause said shank to bind against a surface of its opening, and said flap being movable to release said offset to cause said plate to rebound.
- 30 9. A game board comprising a tray, balls thereon, a table for supporting said tray, ball stalls on said tray, a plurality of openings in said stalls, means in said stalls for

projecting a ball, a cue ball adapted to operate said means, said means consisting of a 35 spring pressed button.

10. A game board comprising a tray, balls thereon, a table for supporting said tray, ball stalls on said tray, a plurality of openings in said stalls, means in said stalls 40 for projecting a ball, a cue ball adapted to operate said means, said means consisting of a spring pressed button, a flap by means of which said cue ball may operate said means.

11. A game board comprising a tray, 45 balls thereon, a table for supporting said tray, ball stalls on said tray, a plurality of openings in said stalls, means in said stalls for projecting a ball, a cue ball adapted to operate said means, said means consisting 50 of a spring pressed button, a flap by means of which said cue ball may operate said means, and guides for directing said cue ball toward said flap.

12. A device as described consisting of a 55 tray having stalls, balls therein, openings in said stalls, means for projecting said balls and means whereby said means may be operated.

In testimony whereof I affix my signature 60 in presence of two witnesses.

WILLIAM M. COOK.
